UNITED STATES PATENT OFFICE

ISAAC VERNON BRUMBAUGH, OF ST. LOUIS, MISSOURI, ASSIGNOR TO AMERICAN STOVE COMPANY, OF ST. LOUIS, MISSOURI, A CORPORATION OF NEW JERSEY

AERATION SHIELD FOR BURNERS OF GAS RANGES

Application filed July 15, 1929. Serial No. 378,434.

This invention relates to improvements in aeration shields for burners of gas ranges and it is particularly intended to be used in connection with the well known closed cooking top with which gas ranges and stoves are constructed.

For many years the American Gas Association has written certain specifications in connection with gas ranges, and manufacturers of gas ranges have been required to comply with the requirements of this association. Comparatively recently this association has written certain specifications and requirements in the operation of what is known as closed cooking top ranges or stoves. Among these specifications it is required that the combustion must be practically perfect as only about 0.078% of carbon monoxide is allowed in the air-free products of combustion, and this same association has required that the cooking top burners of gas ranges must have an efficiency not less than 30%.

It is the primary object of this present improvement to provide a closed cooking top utilizing gas burners that have not only the efficiency required by the association but even greater efficiency, and that so perfect a combustion is provided that the specification of the association in respect to carbon monoxide is complied with.

The present invention relates to a closed cooking top that contains a plurality of front burners (usually two) and a plurality of rear burners (usually two) and that all of the burners are of substantially the same size and all of them are contained beneath the said cooking top.

The inventor of the improvement here involved has spent a great deal of time in experimenting and working out a closed cooking top that will comply with the requirements of the American Gas Association, and has finally succeeded in producing a construction that is well within the said requirements.

Speaking in general terms the requirements have been worked out by forming a compartment that is substantially closed along its front and both sides the compartment having its horizontal wall consisting

of what I term as an aeration shield, the said shield provided with upwardly extending individual collars each collar embracing one burner, or the equivalent of the collar, the burner openings located between the upper edge of the collar and the said horizontal shield.

After long experimentation and tests it was ascertained that in a closed cooking top of the type described and containing front and rear burners that the rear burners received an excessive flow of secondary air, as compared with the secondary air supplied to the front burners, and it became necessary to work out some means whereby the proper amount of secondary air would be supplied to the rear burners and at the same time the proper amount of secondary air be supplied to the front burners. The manner in which this has been done in the present improvement broadly consists in an arrangement whereby all of the burners obtain their secondary air from a common chamber or supply and it was found by utilizing in this combination, means supplied to the rear burners for restricting the supply of secondary air to them that the required thermal efficiency of the front and rear burners was provided, and that therefore I had produced a combination which would meet the requirements of the said association.

I also found that the efficiency of the present invention was very much improved by providing the rear wall of the combustion compartment with a restricted outlet or outlets for the products of combustion to the flue. The previously described arrangement greatly increased the thermal efficiency of the burners and this efficiency was found to be further increased by having the rear wall closed at points substantially opposite the rear burners and to provide the outlet for the products of combustion in a line substantially at the sides of the rear burner.

Additional advantages, operations and improvements will be described hereinafter.

In the drawings:

Figure 1 is a top plan view of the top burner construction involving the present im-

ovement with the removable top or lid portion omitted.

Figure 2 is a front view of Figure 1.

Figure 3 is a cross section on the line 3—3 of Figure 1 with the removable top or lid portion in position.

Figure 4 is a longitudinal vertical sectional view on the line 4—4 of Figure 1.

Figure 5 is a top plan view of the top of the aeration shield.

Figure 6 is a transverse vertical sectional view on the line 6—6 of Figure 5.

Figure 7 is an enlarged vertical sectional view through one of the rear burners embracing collars the same being shown in enlarged sectional view.

Figure 8 is a vertical transverse sectional view on the line 8—8 of Figure 1 showing a portion of one of the front collars and one of 20 the supporting elements of the aeration shield.

Referring now to the drawings in this case and particularly to Figures 1 and 2, the surrounding edge or frame 1 of the top burner portion is shown. The removable top members 2 are shown in Figure 3. Below these removable members is located what I term an aeration shield 3. This aeration shield primarily consists of a horizontal portion.

Projecting upwardly from the surrounding edges of this shield 3 is a vertical wall 4 which extends substantially to the under side of the removable portion 2 of the top of the range. This vertical wall 4 extends upward and 35 serves substantially as a closure for the shield 3 with the exception that the said wall is removed at the rear of the said shield as at the central point 5 and the two end points 6 and 7. The object and operations of these openings 40 will be described hereinafter.

Surrounding the front burners 8 and the rear burners 9 are vertically arranged walls 10 and 11. This aeration shield therefore consists essentially of the horizontal wall 45 portion 3, the peripheral wall portion 4 and the vertically arranged portions 10 and 11 surrounding the said burners. The forming in the rear end of this aeration shield of the passageways 5, 6 and 7 leaves a vertically 50 arranged portion 12 which lies between the said openings and the upper edges of these parts 12 extend outwardly as shown at 13 resting upon an inwardly extending ledge 14 of the surrounding frame 1 while the front 55 portion 4 of the vertical wall that surrounds the edge of the aeration shield also has its end 15 turned outwardly and resting on a ledge 16 of the frame 1.

A flue box 17 extends substantially across 60 the rear end of the frame 1 and the said flue box has its lower end extending around the depending portion 18 of the frame 1 and its end 19 extending against the said wall 12 whereby the products of combustion from the 65 compartment 20 flow through the openings

5, 6 and 7 to the flue box 17 from which box the products pass outward through the flue 21.

By reference to Figure 1 it will be observed that I have provided means for restricting the flow of the secondary air to the rear burners 9 and that this means consists of the projections 22 located between the arms of the burners, there being a space surrounding these projecting arms and the adjacent wall 75 of the radially extending fingers of the burners. These air restricting members serve a very important function in this improvement as will presently appear.

The lighter burner 23 is of the usual construction and the flames therefrom pass through the openings 24 and into the openings 25 formed in the surrounding members 10 and 11 to the gas flowing from the burners 8 and 9 for lighting them.

By reference to Figure 4 it will be observed that the manifolds 26 of the said front burners 8, and 27 of said rear burners 9 are located under the aeration shield 3 and that the shutter portion 28 of the front ends of these manifolds are also located outside of the said aeration shield. A suitable gas manifold 29 is here shown as located under the front edge of the frame 1 and connected with this manifold are the gas valve housings 30 and suitable handles 31 operate the gas valves (not shown) located in the housings 30. It will also be observed that this arrangement brings the mixing tubes or manifolds entirely outside of the aeration shield for a purpose to be presently explained in connection with the operation of this improvement. A gas supply 32 for the pilot light 23 is also provided and receives its gas in the ordinary way for lighting the main burners, and is also outside of said shield.

Located under the burners 8 and 9 is the ordinary removable tray portion 33 and this tray portion forms a chamber 34 that is open at its outer end, though the front end of this chamber may be closed without affecting my present improvement so long as sufficient air flows thereby to supply the wants of the burners.

From the foregoing description it will be observed that the front and rear burners 8 and 9 all communicate with a single common chamber 20. With a gas range having such a construction it was a problem to provide means whereby the front and rear burners would receive the same amount of secondary air because it was found in such a construction that the rear burners receive such an excess supply of secondary air as to make them wholly inefficient and to make them wholly unable to meet the efficiency requirements of the American Gas Association.

In the above combination I found that both the front and rear burners would be supplied with the proper amount of second-

ary air by providing the rear burners with means for restricting the flow of secondary air thereto and I met this problem by providing the aeration shield having vertical 5 collars surrounding the burners and all of the burners communicating with a common compartment or chamber and by providing the rear burners with the restriction, and specifically the restriction here shown 10 consists in having radially inwardly extending members 22 that extend between the arms of the burners, the said arms leaving sufficient space to provide the proper amount of secondary air. Although the front and rear 15 burners received their secondary air from a common chamber I found that the rear burners received an excess of secondary air and I found that I could cut down the excess amount of secondary air supplied to 20 the rear burners by providing them with a restricting means and that this was very much improved by restricting the flow of the products of combustion from the chamber or compartment 2 by such means, for 25 instance as the restrictions 5, 6 and 7 or any restriction that was equivalent thereto. It may be that the excess amount of secondary air to the rear burners while there is 30 no excess air to the front burners is caused by reason of the draft caused by the front burners and that this draft was added to the draft of the rear burners, thereby supplying 35 an excessive draft to the rear burners and thereby an excessive amount of secondary air thereto. At any rate, I have succeeded in combining the front and rear burners in a common chamber to which the combustion of both burners is fed and at the same time I have been enabled to control 40 the amount of secondary air to the rear burners. Of course it is not new to take a single burner and provide it with some restricting means very much like that shown in this application, but it is new so far as 45 I am aware to combine the front and rear burners and to control the amount of secondary air fed to the rear burners while allowing the ordinary amount of secondary air to be fed to the front burners, and yet the front 50 burners not receiving an over supply of this secondary air.

It is of course understood that primary air fed to gas burners is that air which passes in the burner manifold and mixes with the 55 gas thereby providing the ordinary blue flame, while secondary air is the air that is supplied to the flame outside and independently of the manifold.

The mixing tubes or manifolds 26 and 27 60 are located below the aeration shield 3 which is for the purpose of preventing the overheating of the mixing tubes because the products of combustion do not come in direct contact with them.

65 I have found that the distance between

the top 2 and the burner as indicated by X in Figure 3 must be considerably less than the distance between the said top 2 and the aeration shield 3 as indicated by the dotted line Y in Figure 2, in order to obtain the best results in the practice of this improvement. 70

I also find that the collars 10 and 11 should extend above the top of the burner substantially as far as the burner extends above the aeration shield 3 in order to serve to direct the secondary air to the burner flames and also serve to prevent the burned gases which have been formed from being circulated back to the burner flames, that is to say, an aeration shield without these collars the secondary air would not be directed to the burner flames properly, and unsatisfactory combustion would occur because some of the burned gases would return to the flames. 75 80 85

I have been led to the conception of this present invention by reason of the requirements of the American Gas Association, and I have only been enabled to accomplish the above results after long study and experimentation. 90

It will be noted that the pilot light construction extends into what I will designate as the combustion chamber 20 and that the ports 24 for this pilot light are above the base of the aeration shield and that the tube 32 that supplies gas to the pilot light is below the base of the aeration shield. 95

The space between the collars 10 and 11 and the lid or top portion 2 is in reality a restriction which provides only sufficient space for the flame and the passage of the burned gases. 100

While numerous efforts have been made to accomplish the purposes above described, yet so far as I am aware I am the first to accomplish these objects through the means herein described. 105

I desire it understood that variations may be made in the construction and arrangement of the invention without departing from the scope of the invention so long as such changes will come within a liberal interpretation of the attached claims. 110

Having thus described my invention what I claim and desire to secure by Letters Patent is: 115

1. In a range the combination of a substantially closed burner top, an aeration shield located below and separated from the said top thereby forming a combustion chamber, front and rear burners located therein, secondary air restrictions for said burners, said air restrictions for the rear burners being greater than for the front burners, whereby an excessive flow of secondary air to the rear burners is prevented, for the purpose set forth. 120 125

2. In a range the combination of a substantially closed burner top, an aeration shield 130

located below and separated from said top thereby forming a combustion chamber, front and rear burners located therein, said burners having secondary air restrictions therearound, the said surrounding secondary air restrictions for the rear burners being greater than for the front burners, whereby excessive flow of secondary air to the rear burners is prevented and the proper flow of secondary air to both the front and rear burners to maintain an efficient burning of both front and rear burners is accomplished.

In testimony whereof I hereunto affix my signature.
